UNITED STATES PATENT OFFICE.

JOHN AULD, OF HAMDEN, NEW YORK.

BOTTLE.

SPECIFICATION forming part of Letters Patent No. 757,714, dated April 19, 1904.

Application filed August 12, 1903. Serial No. 169,199. (No model.)

To all whom it may concern:

Be it known that I, JOHN AULD, a citizen of the United States, residing at Hamden, in the county of Delaware and State of New York, have invented a new and useful Bottle; and I do hereby declare the following to be a full, clear, and exact description of the invention, such as will enable others skilled in the art to which it appertains to make and use the same.

10 The invention relates to a bottle; and it has for its object to provide a simple, inexpensive, and efficient one adapted after it has received its original contents to effectually prevent fraudulent refilling and sale as an original package and adapted when opened to be sufficiently mutilated to enable such facts to be readily ascertained at a glance, whereby adulteration of its original contents is prevented.

20 With these and other objects in view the invention consists in the novel construction and arrangement of parts hereinafter described and shown, and particularly pointed out in the claim hereto appended.

25 In the drawings forming part of this specification, and in which like numerals of reference designate corresponding parts, Figure 1 is a vertical sectional view of a bottle constructed in accordance with this invention.

30 Fig. 2 is an elevation of a bottle, showing the same before the cap is applied thereto. Fig. 3 is a vertical sectional view of the cap.

Referring to the drawings, 1 designates a bottle provided with a neck having a reduced portion forming a frangible ligament 2, which, as hereinafter explained, is adapted to be readily fractured to enable the upper portion 3 of the neck to be broken off to afford access to a cork or stopper 4, which is fitted in the lower portion 5 of the neck. The frangible ligament is formed by an exterior groove, and the upper portion of the neck is provided at the bottom with an exterior rib or annular enlargement 6, forming an upper shoulder or seat and beveled at the under side and adapted to receive a cap 7, which rests upon the seat and upon the upper edge of the neck. The cap, which may be constructed of metal, glass, or any other suitable material, is of greater diameter

50 than the neck of the bottle to provide an intervening space 8, which in practice is filled with cement or other suitable material, and the said space 8, which is closed at the bottom by the annular enlargement 6, confines the cement. The annular enlargement prevents 55 access to the cement, which cannot, therefore, be removed by a tool, and access to the contents of the bottle can be had only by breaking off the neck.

The upper portion of the neck is provided 60 above the annular enlargement with annular ribs 9, triangular in cross-section and forming beveled upper faces and horizontal lower faces or shoulders, and the cap is provided on the interior of its side walls with ribs 10 and 11. 65 The rib 10, which is located between the top and bottom of the cap, is triangular in cross-section and forms a horizontal upper shoulder and an inclined or beveled lower shoulder or face.

70 The lower rib 11 is rectangular in cross-section and provides an upper horizontal shoulder and a broad lower bearing edge to fit upon the annular enlargement 6 of the upper portion of the neck of the bottle, whereby the 75 annular space between the neck and cap is effectively closed at the bottom.

The cap is provided at the top with a knob or grip, as clearly shown in Figs. 1 and 3 of the drawings.

80 It will be seen that the cap is securely fastened to the upper portion of the neck and that the intervening cement-receiving space is concealed and access thereto effectually prevented when the cap is properly put on the 85 bottle.

What I claim is—

The combination of a receptacle provided at its neck with a frangible ligament and having an exterior annular enlargement above 90 the same to form a horizontal seat, said neck being also provided above the enlargement with triangular ribs shouldered at their lower faces, a cap arranged on the neck and resting upon the upper edges thereof and upon the 95 seat and spaced from the neck at the sides thereof to form an interspace, said cap being provided on the inner faces of the sides with

ribs shouldered at their upper faces, one of the ribs being arranged at the bottom of the cap, a cement filling arranged in the said interspace and securing the cap to the frangible portion of the neck, and a stopper fitted in the neck and extending below the frangible ligament, substantially as described.

In testimony whereof I have hereto affixed my signature in the presence of two witnesses.

JOHN AULD.
